UNITED STATES PATENT OFFICE.

WILLIAM M. SEARBY, OF SAN FRANCISCO, CALIFORNIA.

DESIGN FOR A BED-PAN.

SPECIFICATION forming part of Design No. 25,728, dated June 30, 1896.

Application filed February 8, 1896. Serial No. 578,615. Term of patent 14 years.

To all whom it may concern:

Be it known that I, WILLIAM M. SEARBY, a citizen of the United States, residing in the city and county of San Francisco and State 5 of California, have invented and produced a new and original Design for a Bed-Pan, of which the following is a specification, reference being had to the accompanying drawings, representing the same.

10 Figure 1 of the said drawings is a perspective view of a bed-pan, showing my design. Fig. 2 is a plan or top view; and Fig. 3 is a vertical section taken longitudinally through the plan, Fig. 2, these three views being considered necessary to illustrate fully the form 15 of my new bed-pan.

The leading features of my design consist of a body with an oval top having the usual oblong opening in it located on the shorter 20 axis or diameter of the oval.

The sides of the pan are inclined downward on convex outlines to the bottom, which is flat and of corresponding oval outline, but smaller than the top.

25 The height of the body at the sides or at the ends of the longer axis is greater than at the front and back, and the surface of the

oval top has greater pitch toward the front, while that portion of the top between the rear edge of the central opening and the rim of the 30 pan at the back has greater concavity than the portion of the top surface at the front of the opening.

From an outlet-aperture in the side of the 35 pan a discharge-tube with a screw-threaded end for a cap is fixed at an angle inclining upward and outwardly from the body.

In the said drawings, A indicates the oval 40 top; B, the central opening; C, the flat bottom, and D the convex sides.

E indicates the concavity at the back, and F the outlet-tube and handle.

Having thus described my invention, what 45 I claim as new, and desire to secure by Letters Patent, is—

The design for a bed-pan substantially as herein shown and described.

In testimony that I claim the foregoing I have hereunto set my hand and seal.

WILLIAM M. SEARBY. [L. S.]
